George Hoffman ATTORNEY

UNITED STATES PATENT OFFICE

ISAAC ROSEN, OF BROOKLYN, NEW YORK

NECKTIE CLASP

Application filed March 16, 1928. Serial No. 262,229.

This invention relates to neck-tie clasps, wherein the clasp is permanently attached to a neck-tie as disclosed in U. S. Letters Patent No. 1,170,840, granted to me Feb. 1, 1916; and it is the object of the invention to provide improved means for attaching the clasp to the neck-tie and whereby the clasp may be adjusted to variable positions relative to the attaching means.

10 The foregoing and other objects of the invention will be hereinafter fully described and claimed and are illustrated in the accompanying drawing forming part of this application, in which

15 Figure 1 is a front view, showing a neck-tie attached to a shirt by my new and improved neck-tie clasp, only so much of the shirt being shown as is essential to an understanding of the invention, and the neck-tie 20 being broken away to illustrate the manner of attachment by my improved clasp-attaching means applied thereto; Fig. 2 is a view looking to the rear of Fig. 1; Fig. 3 is a section taken on line 3—3 of Fig. 1, looking 25 in the direction of the arrows; and Fig. 4 is a perspective view of the clasp-attaching means unassembled.

In the drawing, the reference numeral 1 designates a neck-tie having the inner end 2, the outer end 3, lining 4. The front of a shirt is indicated at 5, only so much of the shirt being shown as is essential to an understanding of the invention.

25 In the embodiment of the invention illustrated, I have shown the same for attaching a clasp embodying a pair of jaws 6—7 having laterally extending ears whereby they are pivotally connected as at 8 and normally urged to clamping position by a spring 8' coiled about the pivot and each end anchored at the end of each jaw opposite to the clamping end. One jaw 7 is movably mounted on a pivot-pin 9 fixed in and projecting from one face of a plate 10 of a clamp for attaching the clasp to the neck-tie, the pivot-pin being extended through an opening in the clasp member 7 and upset and whereby the clasp is adapted to have pivotal swinging movement about said pin, as shown in Fig. 45

50 3. The clasp is attached to the neck-tie by

bending tangs 11 at opposite ends of the clamp-plate 10 at right-angles thereto and extending in a direction opposite to the pivot-pin 9, said tangs preferably being sharpened to readily pierce the fabric of the tie as well as the lining 4 and engage in perforations 12 of a plate 13 arranged at the side of the lining and fabric opposite to the clamp-plate 10 and said tangs bent over the face of said plate 13, as clearly shown in Fig. 3. The clamp-plates 10—13 are preferably arranged to overlap the connecting seam 14 of the tie whereby the clamp has a more firm hold upon the tie and prevents fraying and tearing of the same. It will be obvious by the arrangement described that the clasp members 7 may be readily moved to any clasping position by exerting a force thereon against the tension of the spring 8', and, furthermore, that the clasp members may be variably adjusted about the pivot-pin 9 so that when the clasp is released from the shirt it will automatically assume the dotted line position shown in Fig. 2 and permit of the ready removal of the tie.

55 By reference to Fig. 2 it will be seen that the clasp is attached to the back of the outer portion or end 3 of the neck-tie 1 and that the clasp firmly holds that end and the inner end 2 of the tie to the shirt-front 5. It will be observed that the clasp and its clamping means are not visible when the tie is applied to the shirt.

60 By further reference to Fig. 3, it will be seen how the clasp is fastened to the plate 10 of the clamping means and how this plate is secured to the plate 13 and both plates to the fabric of the outer end of the tie and the lining 4 of said end, thereby giving a more firm hold on the tie and preventing the same 65 from getting out of shape, tearing of the fabric, &c.

65 It is my idea to sell neck-ties provided with a clasp permanently attached to the tie by my improved attaching means, and so the 70 clasp will always be available and not get lost. The invention may be manufactured so inexpensively as not to add materially to the cost of the tie to which it is thus attached.

75 It is of course understood that the clasp- 80

attaching means may be secured to the fabric of the tie in any other suitable manner, as by sewing or otherwise, and that changes may be made in the shape of the clasp or the clamping plates, without departing from the scope of the invention as set forth in the appended claims.

What I claim is:

1. In a neck-tie fastener, a clasp, and means to attach the clasp to the neck-tie, comprising a clamp embodying plates arranged at opposite sides of the fabric of the neck-tie, the one plate having tangs to pierce the neck-tie fabric and engage in perforations in the other plate and flanged thereover, and the clamp-plate at the outer side of the tie arranged with a pivot for movably mounting the clasp thereon.
2. In a neck-tie fastener, a clasp comprising a pair of jaws pivotally connected intermediate the ends of the clasp, one of said jaws having a perforation at the side of the pivot connection of the clasp-jaws opposite the jaw end, and clamping means as claimed in claim 1 for attaching the clasp to the neck-tie.

In testimony whereof, I affix my signature.
ISAAC ROSEN.
